(57) **CLAIM**

The ornamental design for a vase, as shown and described.

DESCRIPTION

FIG. 1 is a perspective view of the vase showing my design. FIG. 2 is a front elevational view of the vase.

FIG. 3 is a rear elevational view thereof.

FIG. 4 is a top plan view thereof.

FIG. 5 is a bottom plan view thereof.

FIG. 6 is a right side elevational view thereof; and,

FIG. 7 is a left side elevational view thereof.

Regions of the item within the broken lines in FIGS. 1 and 4 form no part of the claimed design.

1 Claim, 4 Drawing Sheets
